[57] ABSTRACT

An on-off fluid control device in which a body member has a passage extending therethrough between an inlet adapted for connection to a source of fluid under pressure and an outlet adapted to be connected to a head for discharging the fluid. A gate valve is operable to selectively close the passage and open the passage in response to temperature variations occurring in the vicinity of the body member. The gate valve is initially maintained in its open position despite the existence of a temperature corresponding to the temperature that would normally move it to its closed position, to prevent jamming or locking of the valve. An assembly incorporating the control device in combination with a pressure responsive control device and a fire protection system incorporating the control device.

FIG. 1.

FIG. 2.

FIG. 3.

FIG. 4.

TEMPERATURE RESPONSIVE ON-OFF FLUID CONTROL DEVICE AND A CONTROL ASSEMBLY AND FIRE PROTECTION SYSTEM INCORPORATING SAID DEVICE

BACKGROUND OF THE INVENTION

This invention relates to a fluid flow device and a fire protection system incorporating a plurality of such devices and, more particularly, to such a device and system in which the flow of fluid is controlled in response to temperature variations in the vicinity of the device. This invention also relates to an assembly in which fluid flow is controlled in response to variations in temperatures and in response to the pressure of the fluid.

Fire protection systems have traditionally employed sprinkler heads which are actuated by a thermal link in response to an elevated temperature to open the head and permit the discharge of extinguishant therefrom. In these devices, once the fusible link has melted, or fused, the head remains open despite later changes in the condition of the fire situation in the vicinity of the head. As a result, the open head remains open despite a later reduction in the intensity of the fire in its immediate vicinity to an extent that the water discharging from the head would not be needed at that particular location, which would therefore rob the remaining heads located at a more advantageous position relative to the fire from valuable extinguishant.

Another type of difficulty that exists in the use of these type systems, as well as in the use of any similar type device employing a movable valve member for controlling the flow of fluid, is the problem of the valve member jamming, or locking, in its closed position as a result of corrosion, rust, or the like, especially after prolonged periods of non-use. Of course, when the valve member jams in its closed position when employed in a fire protection system, the results could be disastrous.

SUMMARY OF THE INVENTION

It is, therefore, an object of the present invention to provide a fluid flow control device in which the flow of fluid through a passage is selectively controlled in response to temperature variations in the immediate vicinity of the device.

It is another object of the present invention to provide a control device which can be connected between a discharge head and an extinguishant supply conduit in a fire protection system in a manner to permit the flow of fluid to and through the head in normal response to a fire condition, yet prevent the flow if the fire situation changes to the extent that the temperature in the vicinity of the head is reduced.

It is a still further object of the present invention to provide a fire protection system incorporating a plurality of the above-mentioned fluid control devices.

It is a still further object of the present invention to provide an assembly incorporating the fluid flow control device of the present invention in combination with a device which also controls the flow of the fluid in response to variations in the pressure of the fluid.

Toward the fulfillment of these and other objects, the fluid flow control device discussed above includes a body member having a passage therethrough and extending between an inlet adapted to be connected to a source of fluid under pressure and an outlet adapted to be connected to a head for discharging said fluid, valve

means supported by said body member and movable between a first position in which it blocks the flow of fluid through said passage and a second position in which it permits the flow of fluid through said passage and to said head, and control means normally maintaining said valve means in said second position, said control means moving said valve means to said first position in response to the temperature in the vicinity of said body member attaining a predetermined, relatively high, value and then falling to a predetermined, relatively low, value.

BRIEF DESCRIPTION OF THE DRAWINGS

FIG. 1 is a vertical cross-sectional view of the fluid flow control device of the present invention;

FIG. 2 is a horizontal cross-sectional view taken along the line 2-2 of FIG. 1;

FIG. 3 is a reduced, partial elevational view depicting a fire protection system incorporating a plurality of the fluid control devices of FIG. 1; and

FIG. 4 is a vertical cross-sectional view of an assembly incorporating the fluid flow control device of the present invention in combination with a pressure responsive control device.

DESCRIPTION OF THE PREFERRED EMBODIMENT

Referring specifically to FIG. 1 of the drawings, the reference numeral 10 refers in general to the flow control device of the present invention which consists of a housing 12 having a passage 14 extending therethrough from an inlet opening 14a to an outlet opening 14b. The passage 14 includes an enlarged portion 14c which forms a chamber, for reasons to be described in detail later. That portion of the housing 12 defining the inlet opening 14a of the passage 14 is externally threaded, as shown at 16, while a portion of the inner surface of the passage 14 adjacent the outlet opening 14b has an internally threaded portion, as shown at 18.

A gate valve member 20 is disposed in the housing 12 and is adapted to move laterally from an open position shown by the solid lines in FIGS. 1 and 2 to a closed position as shown by the dashed lines in which it extends across the passage 14. The valve member 20 is mechanically connected to a thermal valve motor, shown schematically by the reference numeral 22, which operates to move the valve member to and from its open and closed positions in response to thermal variations in the vicinity of the motor. More specifically, the motor 22 operates to move the valve member 20 to the left, as viewed in FIG. 1, towards its closed position in response to a predetermined, relatively low temperature occurring in the immediate vicinity of the motor, and operates to move the valve member to the right towards its open position in response to a predetermined, relatively high temperature. Since the thermal valve motor 22 may be of a conventional type such as the type that operates by the expansion and contraction of wax or other similar material, it is not shown or described in any further detail.

An arcuate notch 24 is provided in a portion of the wall of the housing 12 defining the passage 14 in alignment with the valve member 20 for receiving the leading end portion of the latter member in its closed position.

A restraining sleeve 26 is mounted for slidable movement inside the passage 14 from an upper position

shown by the solid lines to a lower position shown by the dashed lines. A notch 28 is formed in the outer surface of the sleeve 26 which, in the upper position of the sleeve, receives an end portion of the valve member 20 when the valve member is in its open position, to prevent movement of the valve member to its closed position.

The upper end of the sleeve 26 is open and a bottom plate 30 extends across the lower end thereof. A plurality of openings 31 are formed through the bottom plate 30 as well as the lower portion of the wall of the sleeve 26, to permit the flow of fluid therethrough for reasons that will be explained in detail later. The sleeve 26 is adapted to slide downwardly in the passage 14 to its lower position shown by the dashed lines in FIG. 1 in which it releases the valve member 20, under conditions that will be described in detail later.

A slot 32 is provided in the sleeve 26 and a projection 34 is formed on the inner wall of the housing 12 defining the passage 14 which extends in the slot and thus limits the downward movement of the sleeve 26 in the passage 14. A leaf spring 40 is mounted on the inner wall of the housing 12 defining the passage 14 and is adapted to spring outwardly into the passage after the sleeve 26 moves to its lower position to retain the sleeve in this position.

The externally threaded portion 16 of the housing 12 is connected to a conduit system or the like via an externally threaded T-connector, shown partially by the reference numeral 42, for supplying fluid, such as water, to the inlet 14a of the housing. An externally threaded portion of a discharge head, shown partially by the reference numeral 44, is threadedly engaged with the threaded portion 18 of the housing 12 to discharge the water after it passes through the passage 14. The head 44 may be of the type which is actuatable by a thermal fuse, or the like, which opens the head and permits the flow of water therethrough. The type of head that can be used is disclosed in applicant's U.S. Pat. No. 3,743,022 also assigned to the assignee of the present invention. The disclosure of the patent is hereby incorporated by reference.

For the purposes of example, it will be assumed that the thermal valve motor 22 is adapted to move the gate valve member 20 to its closed, flow preventing position, shown by the dashed lines in FIGS. 1 and 2, in response to a temperature in the vicinity of the motor of approximately 100° or less, that the head 44 is adapted to open in response to a temperature of approximately 165°F., and that the motor 22 is adapted to move the gate valve 20 to its open, flow permitting position, shown by the solid lines in FIGS. 1 and 2 in response to a temperature of approximately 280° or greater.

The device is installed in the position shown in FIG. 1, i.e., with the sleeve 26 in its upper position shown by the solid lines in which it prevents movement of the valve member 20 to the left despite the existence of a relatively low temperature and the resultant urging of the valve member by the valve motor 22 in this direction.

Assuming a fire occurs in the vicinity of the device 12 of a sufficient magnitude to cause a fusing of the fusible member (not shown) associated with the head 44 and an opening of same, flow will be permitted through the T-connector 42, the passage 14 including the holes 31 in the sleeve 26, and out through the outlet 14b as shown by the flow arrows for passage to the head and

discharge toward the fire. If the temperature rises to at least 280°F., the thermal valve motor 22 operates to move the valve member 20 from its open position shown by the solid lines a slight distance to the right as viewed in FIG. 1. The sleeve 26 will then be released and will be forced downwardly in the passage 14 under the action of the pressure differential created by the water flowing through the passage 14 until it reaches its lower position shown by the dashed lines, in which further downward movement is prevented by the projection 34 engaging the upper portion of the slot 32. In this position, the openings 31 in the wall of the sleeve 26 are located in the enlarged portion 14c of the passage 14 which provides ample space for the water discharging in a lateral direction therethrough as shown by the flow arrows in FIG. 1, so not as to substantially impair the flow rate through the passage 14.

In the event the fire later subsides to an extent that the temperature in the vicinity of the motor 22 drops to 100°F. or less, the motor will move the valve member 20 to its closed, or flow preventing position, shown by the dashed lines to prevent additional flow through the passage 14. As a result, water is prevented from being indiscriminantly discharged from this particular head in a relatively inefficient manner, and is thus saved for use elsewhere.

Of course, in the event the temperature in the vicinity of the motor 22 later rises to or above 280°F., the motor will move the valve 20 to its open position to permit further discharge through the passage 14 and to the head 44.

It can be appreciated that the sleeve 26, in initially maintaining the valve member in its open position, prevents or at least reduces the possibility of corrosion, rust, or the like, jamming the valve member 20 in a permanently closed position.

FIG. 3 depicts a plurality of control devices 10 of the present invention incorporated in a fire protection system shown installed in a space shown in general by the reference numeral 50. In particular, a pair of branch lines 52 are supported in an elevated position in the space 50 and extend to either side of a crossmain shown in section by the reference numeral 54, with a plurality of the T-connectors 42 extending downwardly at spaced intervals along each branch line 52. Each control device 10 is connected to the pendant portion of a T-connector 42 and receives a discharge head 44, with the connections being made in the manner described above.

As stated above, the heads 44 may be in the form of direct discharge nozzles disclosed in the above patent and are disposed directly over a plurality of materials a-f to be protected from fire. Alternatively, the heads 44 can be in the form of conventional sprinkler heads in which the water is discharged against a serrated disc to create a mist-type spray pattern in a well-known manner.

FIG. 4 depicts a control assembly incorporating the control device 10 in combination with a device for also controlling the flow of fluid in response to variations in its pressure. In general, the device 10 is connected at its discharge end to a discharge head 44 which threadedly engages the externally threaded portion 18 of the housing 12 as in the previous embodiment.

The pressure responsive control device is shown in general by the reference numeral 60 and consists of a housing 62 having a passage 64 extending therethrough

from an inlet opening 64a to an outlet opening 64b. That portion of the housing 62 defining the inlet opening 64a of the passage 64 is externally threaded, as shown at 66 and is connected to a T-connector, shown partially by the reference numeral 42, of a fluid conduit system, while a portion of the inner surface of the passage 64 adjacent the outlet opening 64b is internally threaded, as shown at 68 to mate with the threaded portion 16 of the device 10.

A chamber 70 is formed in the housing 62 in communication with the passage 64 and receives a flow control unit shown in general by the reference numeral 72. The unit 72 is formed by a hollow central portion 74 having two hollow stem portions 76 and 78 extending from opposite sides thereof. The stem portions 76 and 78 extend through openings 80 and 82 formed in the housing 62, with the free end portions of each stem portion projecting slightly outwardly from the housing 62.

The central portion 74 of the flow control unit 72 is defined in part by a slightly flexible, disc-like member 84 which is adapted to move from an expanded position shown by the solid lines in FIG. 4 in which it is of a substantially semi-spherical shape, to a retracted position shown by the dashed lines in which it takes a substantially concave shape. In its expanded condition, the movable member 84 seats against a seal ring 86 disposed within a cut-out shoulder portion in the interior surface of the housing 62, to seal off the flow of fluid through the passage 64. In the retracted position of the movable member 84, the seal is broken and fluid can flow from the inlet opening 64a, through the upper portion of the passage 64 as viewed in FIG. 1, through the chamber 70 and the lower portion of the passage 64 to the outlet opening 64b, and to the inlet 14a of the control device 10, as shown by the flow arrows.

The flow control unit 72 contains a pressurized fluid, such as gas, which exerts an upwardly directed force against the movable member 84 to urge it upwardly against the seal ring 86 to prevent the flow of fluid through the passage 64. However, this force is selected so as to be less than the downwardly directed force against the movable member 84 caused by a predetermined fluid supply pressure which can be attained in the upper portion of the passage 64. As a result, the movable member 84 will move to its retracted position in response to the pressure of the fluid in the upper portion of the chamber 64 attaining or exceeding this predetermined value, to permit the flow of fluid through the passage 64.

A tip 90 of a fusible material is formed on the end of each stem 76 and 78 of the flow control unit 72. The tips 90 normally seal the pressurized gas in the flow control unit 72 and are adapted to melt at a predetermined temperature, such as 500°F., to permit the release of the pressurized gas from the unit for reasons that will be described in detail later.

The assembly shown in FIG. 4 is installed in the condition shown in the drawings, i.e., with the valve member 20 of the control unit 10 in its open position and the sleeve 26 in its upper position in which it prevents closing of the valve member despite relatively low temperature existing in the vicinity of the valve 22.

Assuming the T-connector 42 is connected to a conduit system containing water, and assuming the valve motor 22 and head 44 respond to the same temperature as discussed in the previous embodiment while the fusi-

ble tips 90 are adapted to melt at approximately 500°F., the operation would be as follows.

If the pressure of the water in the upper portion of the passage 64 acting on the movable member 84 of the flow control unit 72 is less than a predetermined value, the pressurized gas in the latter unit will force the member 84 upwardly into a sealing engagement with the seal ring 86 thus preventing the flow of water through the housing 62. Therefore, no water would be introduced to the control unit 10 or to the head 44 despite existence of temperatures sufficient to activate the valve motor 22 and open the head 44.

However, if the water pressure in the system is of a value sufficient to force the movable member 84 downwardly to the position shown by the dashed lines against the force of the pressurized gas, the water will pass into and through the chamber 70, through the lower portion of passage 64 and outwardly through the outlet 64b, where it is introduced into the inlet 14a of the passage 14 of the control unit 10. Upon a fire occurring in the vicinity of the assembly of a sufficient magnitude to raise the temperature in the vicinity of the assembly to at least 165°F., and cause a fusing of the fusible member (not shown) associated with the head 44 and an opening of same, flow will be permitted from the control unit 60 through the passage 14 of the unit 10 including the openings 31 in the sleeve 26, and out through the outlet opening 14b to and through the head for discharge toward the fire. If the temperature rises to at least 280°F., the thermal valve motor 22 operates to move the valve member 20 from its open position, shown by the solid lines, a slight distance to the right as viewed in FIG. 1. The sleeve 26 will then be released and will be forced downwardly in the passage 14 under the action of the pressure differential created by the water flowing through the passage, until it reaches the position shown by the dashed lines, in which further downward movement is prevented by the projection 34 engaging the upper portion of the slot 32. In this position, the openings 31 of the sleeve 26 are disposed in the enlarged portion 14c of the passage 14 which provides ample space for the water discharging in a lateral direction therethrough as shown by the flow arrows so not as to substantially impair the flow rate through the passage 14.

In the event the fire later subsides to an extent that the temperature in the vicinity of the motor 22 drops to approximately 100°F. or less, the motor will move the valve member 20 to its closed or flow preventing position shown by the dashed lines to prevent additional flow through the assembly.

Of course, in the event the temperature in the vicinity of the motor 22 later rises to or above 280°F., the motor will move the valve 20 to its open position to permit further discharge through the passage 14 and to the head 44.

During any portion of the above operation of the control device 10, should the water pressure in the system drop below the above-mentioned predetermined value, the pressurized gas within the flow control unit 72 will again force the movable member 84 upwardly against the seal ring 86 to prevent any additional flow of fluid through the passage 64 and therefrom to the control device 10 and the head 44, regardless of the temperature existing at the time, as long as it is less than 500°F.

However, if the temperature in the vicinity of the body member 62 rises to approximately 500°F. or greater and thus melts either fusible tip 90, the pressurized gas in the flow control unit 72 will be allowed to escape, the movable member 84 will move downwardly under the force of the water, regardless of the latter's pressure, and the water will flow through the housing 62 to the device 10 where it is subject to the above-mentioned further control.

It is thus seen that the assembly of FIG. 4 allows a comprehensive control over the water in response to its pressure and temperature during all stages of fire fighting while minimizing the possibility of stoppage due to corrosion.

A plurality of assemblies of FIG. 4 can be installed in a fire protection system in a manner identical to that shown in FIG. 3. Also, one or more assemblies can easily be installed in an existing system by simply inserting it between a conventional discharge head and the conduit system supplying the head.

It is understood that variations may be made in the foregoing without departing from the scope of the invention. For example, the control device of FIG. 1 as well as the control assembly of FIG. 4 can be used in environments other than fire protection. Also, both the essential components of the control device 10 and the control device 60 may be incorporated in the same housing or, alternatively, may be incorporated in the housing, or main body portion, of a discharge head.

Of course, still other variations of the control device, system and assembly disclosed above can be made without departing from the scope of the invention as defined in the appended claims.

I claim:

1. A fluid control device comprising a body member having a passage therethrough and extending between an inlet adapted to be connected to a source of fluid under pressure and an outlet adapted to be connected to a head for discharging said fluid, valve means supported by said body member and movable between a first position in which it blocks the flow of fluid through said passage and a second position in which it permits the flow of fluid through said passage and to said head, and control means normally maintaining said valve means in said second position, said control means moving said valve means to said first position in response to the temperature in the vicinity of said body member attaining a predetermined, relatively high, value and then falling to a predetermined, relatively low, value.

2. The device of claim 1 wherein said control means comprises drive means responsive to a said relatively low temperature for urging said valve means to said first position, and to a said relatively high temperature for moving said valve means to said second position, and means for maintaining said valve means in said second position despite the existence of said relatively low temperature until said relatively high temperature initially occurs.

3. The device of claim 2 wherein said drive means comprises a thermal valve motor operatively connected to said valve means.

4. The device of claim 2 wherein said maintaining means comprises a member disposed in said passage and adapted to engage said valve means and prevent movement of said valve means to said first position despite the existence of said relatively low temperature, said member adapted to release said engagement in re-

sponse to initial movement of said valve means toward said second position.

5. The device of claim 1 wherein said control means is adapted to move said valve member back to said second position in response to the temperature again rising to said relatively high value.

6. A fire protection system comprising conduit means disposed in a space to be protected from fire and adapted to be connected to a source of extinguishant, at least one body member connected to said conduit means and having a passage therethrough extending between an inlet registering with said conduit means and an outlet, a discharge head connected to said outlet for discharging said fluid, valve means supported by said body member and movable between a first position in which it blocks the flow of fluid through said passage and a second position in which it permits the flow of fluid through said passage and to said head, and control means normally maintaining said valve means in said second position, said control means moving said valve means to said first position in response to the temperature in the vicinity of said body member rising above a predetermined value and then falling to or below said value.

7. The system of claim 6 wherein said control means comprises drive means responsive to a said relatively low temperature for urging said valve means to said first position, and to a said relatively high temperature for moving said valve means to said second position, and means for maintaining said valve means in said second position despite the existence of said relatively low temperature until said relatively high temperature initially occurs.

8. A fluid control assembly comprising a housing means having a continuous passage extending therethrough between an inlet adapted to be connected to a source of fluid under pressure and an outlet adapted to be connected to a head for discharging said fluid, valve means supported by said housing and movable between a first position in which it blocks the flow of fluid through said passage and a second position in which it permits the flow of fluid through said passage, control means normally maintaining said valve means in said second position, said control means moving said valve means to said first position in response to the temperature in the vicinity of said body member attaining a predetermined, relatively high, value and then falling to a predetermined, relatively low, value; a movable member normally blocking said passage and having one side exposed to fluid pressure in said passage, and means including said movable member for defining a closed chamber for containing a pressurized fluid, said pressurized fluid normally forcing said movable member into said passage blocking position, said movable member adapted to move from said passage blocking position in response to the fluid pressure in said passage exceeding a predetermined value sufficient to overcome the force of said fluid in said chamber, to permit the flow of fluid in said passage.

9. The assembly of claim 8 wherein said housing means comprises a pair of body members connected together, and having a pair of passages respectively extending therethrough to form said continuous passage.

10. The assembly of claim 8 further comprising means responsive to presence of a temperature in the vicinity of said body member greater than said relatively high temperature, to permit the escape of said

fluid from said chamber and permit said movable member to be forced from said passage blocking position by the fluid in said passage, regardless of the pressure of said fluid.

11. The assembly of claim 8 wherein said movable member is adapted to move back to said passage blocking position in response to the fluid pressure in said passage dropping below said predetermined value.

12. The assembly of claim 8 wherein said control means comprises drive means responsive to a said relatively low temperature for urging said valve means to said first position, and to a said relatively high temperature for moving said valve means to said second position, and means for maintaining said valve means in said second position despite the existence of said relatively low temperature until said relatively high temperature initially occurs.

13. The assembly of claim 12 wherein said drive means comprises a thermal valve motor operatively connected to said valve means.

14. The assembly of claim 12 wherein said maintaining means comprises a member disposed in said passage and adapted to engage said valve means and prevent movement of said valve means to said first position despite the existence of said relatively low temperature, said member adapted to release said engagement in response to initial movement of said valve means towards said second position.

15. The assembly of claim 8 wherein said control means is adapted to move said valve member back to said second position in response to the temperature again rising to said relatively high value.
